CLAIM

The ornamental design for a hanging rack for sports equipment, as shown and described.

DESCRIPTION

FIG. 1 is a perspective view of a hanging rack for sports equipment according to the present invention;

FIG. 2 is a top plan view thereof;

FIG. 3 is a front elevational view thereof;
FIG. 4 is a side elevational view thereof;
FIG. 5 is a rear elevational view thereof; and,

FIG. 6 is a bottom plan view of FIG. 3 thereof.
